CLAIM

The ornamental design for a golf ball, as shown and described.

DESCRIPTION

FIG. 1 is a perspective view of a golf ball showing the new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof; and,

FIG. 7 is a bottom plan view thereof.

The shading shown in the drawings represents a contrast in appearance.

The broken lines shown in the drawings are for the purpose of illustrating portions of the golf ball that form no part of the claimed design.
